(57) **CLAIM**

The ornamental design for a volcano climber, as shown and described.

DESCRIPTION

FIG. 1 is a perspective view of a volcano climber;
FIG. 2 is a second perspective view showing the top thereof;
FIG. 3 is a top plan view thereof;
FIG. 4 is a left-side elevational view thereof, the right-side being substantially a mirror image thereof;
FIG. 5 is a bottom plan view thereof;
FIG. 6 is a front elevational view thereof, the rear being substantially a mirror image;
FIG. 7 is an exploded perspective view showing the component parts of the volcano climber, namely front and rear upper panels, front and rear intermediate panels, front and rear lower panels, ladders and platform; and,
FIG. 8 is a front and left-side perspective view of a second embodiment of the volcano climber design, the right-side view being substantially identical to the left-side view, the rear view, the bottom view and the top view being substantially unadorned.
